H. Aiken,

Tool Handle.

Patented Dec. 16, 1833.

Dec. 16, 1833

379

1834 X J. Gorwick Aiken.
Letters Patent

The Abolition referred to in these Letters Patent and making part of the same, containing a description in the words of the said Gorwick Aiken, howe-
self of his improvement, being a socket for holding awls & other tools.

Be it known that J. Gorwick Aiken of Dracut, Middlesex County,
of Dracut, Massachusetts, have made an improvement in the useful
arts, being a socket, for holding awls, and other tools, called "Aiken's
Awl-Socket" which is described as follows.

This socket is made of brass, or other metal in two equal parts,
connected together by a root at the small end. Its whole length is $1\frac{1}{2}$
inch. The large end is made square $\frac{1}{4}$ inch, the remainder of the length
is made round, $\frac{1}{2}$ inch diameter on the largest part, and tapered to
 $\frac{3}{16}$ " at the small end. A cavity $\frac{3}{8}$ " inch in length and $\frac{1}{8}$ " in
diameter, is made in the shape of a half square, or half round in each
part on the large end to receive the shank of the tool.

The size and taper may be varied. The socket is to be placed on
a handle which confines the tool on the socket.

What I claim as my invention and desire to secure by Letters Patent,
is the before described socket for holding awls, and other tools. —
